HARRISON GRAMBO, OF PHILADELPHIA, PENNSYLVANIA.

Letters Patent No. 60,718, dated January 1, 1867.

IMPROVED MACHINE FOR MANUFACTURING CANDLES.

The Schedule referred to in these Letters Patent and making part of the same.

TO ALL WHOM IT MAY CONCERN:

Be it known that I, HARRISON GRAMBO, of the city and county of Philadelphia, and State of Pennsylvania, have invented certain new and useful improvements in Machines for Manufacturing Candles; and I do hereby declare the following to be a full, clear, and exact description of the nature, construction, and operation of the same, reference being had to the accompanying drawings, which are made part of this specification, and in which—

Figure 1 is a plan of my improved machine.

Figure 2 is a longitudinal section of the same in the plane indicated by the line x x , fig. 1.

Figures 3, 4, and 5 are transverse vertical sections, whose respective planes are indicated by the red lines w w , y y , and z z , fig. 1, the arrows on the several red lines showing the direction from which the corresponding figures are drawn.

Figure 6 is a detached view, which will be hereinafter particularly referred to.

Similar letters of reference indicate corresponding parts in the several figures.

In the machine, the subject of this application, the candle material, either in a cold, solid, or warm fluid state, is supplied to receiving and reducing mills, whence it is forced between a series of knives, and, at every complete operation of the machine, deposited in front of horizontal pistons, which, moving toward the centre of the machine from the opposite sides thereof, force the candle material through transverse passages to the longitudinal centre of the machine, and leave it just below a vertically-moving plunger, whereby it is forced downward into central longitudinal chamber leading directly to the moulds wherein the candles are formed. Within this central longitudinal chamber work the plunger which forces the material into the moulds, the pistons which form the candle-tips and eject the candles from the moulds, and the wick-tubes which place the wicks in position within the candle moulds. The candle-mould pistons have motion both simultaneously with, and independently of, the plunger which forces the material into the moulds, so that when the candle material has been forced into the moulds, the plunger recedes from the latter, while the pistons are advanced through the plunger and moulds by special actuating devices; and, having ejected the candles from the moulds, the pistons are, by a sudden impulse, thrown back into the plunger, thus clearing the moulds in time to enable them to be refilled by the forward motion of the plunger. A pair of double-jawed clamps operating at the outer ends of the moulds seize the wicks as soon as the candles are ejected, and hold them while under the action of the knife, which severs each wick at a point between the tip of the candle already formed and the butt of the succeeding candle within the mould; the clamps also affording a bearing for the candles while in process of formation. While the wicks are held by the clamps, the wick-feeding tubes recede within the plungers, leaving the wicks in a central position within the moulds. The candles, when ejected from the moulds, enter a corresponding series of tubes formed in a box which is advanced to receive and support the candles while the wicks are being severed by the knife. These receiving tubes are also designed to give additional polish and solidity to the candles, as hereinafter explained; and when the candles are ejected therefrom, they are gently deposited upon a pair of parallel arms or rails, which, after receiving the candles, are lowered so as to deposit the candles in a complete condition upon an endless band, which conveys them away, to be stored, boxed, or otherwise disposed of.

In order that others skilled in the art to which my invention appertains may be enabled to fully understand and use the same, I will proceed to describe it in detail with reference to the annexed drawings.

A A¹ may represent the several parts of the frame which supports the various members of the candle-manufacturing mechanism. B B are the receiving and reducing mills or chambers into which the tallow, spermaceti, or other candle material is supplied as the operation progresses. These chambers, B B, are located at the opposite sides of the machine, and in each chamber, B, is journalled a vertical shaft, having a spiral rim or flange, C. The shafts C C, together with their spiral rims C' C', receive motion through the bevel cogs, D D¹ D¹, from the transverse shaft E, which is rotated by means of pulleys F F¹, band F², shaft G; bevel cogs H H¹, and line shaft I, the latter being driven from the main driving shaft, J, through the bevel cogs I I¹. The driving shaft, J, may derive its power from any desired source. I have shown the steam boiler, K, and steam pipe, K¹, for supplying steam to the spaces, b, between the jackets B¹ B¹ and the receiving chambers

B B. These means of heating may be employed when the candle material is supplied to the receiving chambers in a cold condition, for the purpose of reducing the same to the desired pulpy or mouldable state; but when the material is to be supplied in a hot, fluid state, the spaces b are filled with ice, or some freezing mixture, and hence the steam apparatus may be dispensed with. L L are pistons, which are moved transversely toward and from the centre of the machine, and are fitted to slide within the transverse chambers or passages, L' L', through which the candle material is forced to the lower end of the central chamber M, in which works the vertically reciprocating plunger, N. O O represent a series of knives, between which the candle material is forced from chambers, B B to L' L' by the rotation of the spiral rims O' O'. The pistons L L are actuated by the toggle joints m m, and rods m² m² which toggles are attached to the extremity of a vibrating lever, P P, pitman p of which is jointed to a crank on the main driving shaft J. The plunger N is also operated by the lever P P being connected to the latter by the rod N'. The shaft, P', of the lever P P, is supported in a suitably elevated position by the brackets P² P², which rise at each side of the machine, and have their attachment upon the upper side rails of the frame A. Q is a horizontal chamber extending beneath, and communicating with the chamber M, and hence it also communicates with the transverse passages L' L'. R R R R represent the moulds into which the candle material is forced from the chamber Q by the horizontal plunger S, which latter is reciprocated within the chamber Q by means of the connecting-rods s s, which are operated by the cranks, j j on the driving shaft J. The moulds, R, are fixed immovably in the case or box R', and may be surrounded with ice, cold water, or any desired cooling medium, for the purpose of solidifying and indurating the candle material when in the moulds. S' S' S' S' (see fig. 6) are cylindrical pistons, which are adapted to slide into and out of corresponding chambers formed in the body of the plunger S. These pistons are attached to rods, s' s' s' s', which receive an intermittent motion from the cogged segment S' and rack-bar S', the segment being applied to the driving shaft J, and the rack-bar arranged to slide between suitable guides s' s'. During the engagement of the cogged segment S' and rack-bar S', with each other, the rods, s', are advanced or moved toward the moulds, thereby projecting the pistons, S', from their chambers in the plunger S, and causing them to enter the corresponding moulds, R, so as to eject the candles therefrom. This ejecting action of the pistons takes place after they have been forced up to the receiving ends of the moulds R, to which point they are carried by the motion of the plunger S, the pistons being moved along simultaneously with the plunger by the abutment of their ends against the bases of the several chambers in which they are situated. Every time the continued rotation of the shaft J carries the segment S' out of engagement with the rack-bar S', the latter is subjected to the unresisted action of a spring, S', which jerks the pistons S' back into their chambers in the plunger. a a a represent the wick-tubes passing through the plunger S and pistons S'; the rod check lines representing the wick as passing through the said tubes from the reels T T, which are supported and journalled in the bent arms a' a', the lower extremities of which are attached to the transverse bar, a'', which connects the ends of the wick-tubes. To the ends of this connecting-bar, a'', are jointed the ends of the rods a', which, by crank-connection with the driving shaft J, communicate motion to the wick-tubes. The wick tubes, a, correspond in number with the pistons S' and moulds R, and they work through the plunger S, pistons S', and moulds R, in the manner to be hereinafter explained. In operation, the tubes a pass through the moulds R, and deliver the end of the wicks to the clamps d d, which come together and grasp the wicks so as to hold them centrally within the moulds while the tubes recede from the moulds to give place to the candle material which is forced therein by the advancing plunger S and pistons S'. When the tubes recede from the moulds, the reels, T T, undergo a limited rotation, so as to pay off sufficient wick for the next operation. The let-off motion of the reels is limited by the double dog, U, which is pivoted upon the upright u, and when down, arrests the motion of the reels by contact with the pins, t t, on the latter. The dog is elevated at the proper time, so as to release the reels, by the contact of its curved back with the upper edge of the slot in the plate, V, through which the arm of the dog is allowed to play. The detaining end of the dog, U, falls by gravity to arrest the reels T. The jaws, d d, have three important functions, viz, first, to hold the wicks within the moulds during the retreat or receding movement of the wick tubes; second, to close and constitute a common base for the outer ends of the candle moulds while the candle material is being forced into the same; and, third, to hold the wick while under the action of the knife, W, which severs that portion of the wicks which belongs to the formed and ejected candles from that which is yet within the moulds. A sectional view of the clamps d d may be seen in fig. 4, from which the action of the wick-cutting knife between their double jaws will be readily understood. An elevation of the clamps and their appendages is represented in fig. 3; but fig. 4 more clearly illustrates the operation of the devices which open and close the clamps, and I shall now proceed to describe said devices. I' is a bevel cog-wheel keyed to the line shaft I, and meshing with cog-wheels I' I', which are thereby made to communicate a rotary motion to the vertical shafts I' I', which, through the gearing I' I', impart their rotary motion to the horizontal shafts I' I', which, through the gearing i i d' d', give motion to the short rotary shafts d' d', which bear the cams d' d', which work within the bows or curved bars, d' d', attached to the clamps d d. At every revolution the cams d', acting upon friction-rollers d'', move the bows vertically, but in opposite directions, thus opening the clamps d d. As soon as the cams d' suspend their action upon the bows, the latter are quickly thrown toward each other by the springs d' d''. Hence, as often as the clamps d are opened by the cams d', they are closed by the springs d''. These springs, d'', encircle vertical rods, the upper ends of which have rigid bearings on the curved cross-bar D', which is supported upon the bearing frame D', while the lower end of the spring's rods rest upon the box R', which contains the moulds R. The knife, W, is confined by suitable guides, and is depressed by the cam w, which is revolved by the uppermost of the shafts d'. Simultaneously with the depressing action of this cam, w, the knife, W, is drawn laterally by the eccentric, w', on the line shaft, I, acting through the connecting-rod w' (see fig. 3.) This gives the knife a draw cut, which is best adapted to sever the wick. As often as depressed, the knife W is raised by the springs,

ω^3 , so as to be within suitable proximity to the cam ω to admit of a repetition of its action. Y represents a box containing a series of tubes, Y^1 , corresponding in number and size with the moulds R . The tubes are arranged in line with the moulds R , and their box, Y , is fitted to slide upon the rods, Z , toward and away from the mould box R^1 . The box, Y , is carried up to the moulds by the operation of the cogged segment, G^1 , on shaft G , upon the longitudinal rack-bar, G^2 , which is attached to the box Y . When the cogged segment has run itself out of gear with the rack-bar G^2 , the box Y is retracted from the moulds R by the springs Z^1 which encircle the rods Z . Y^2 are a series of stationary pistons or cylinders, which, when the box Y is retracted, enter the tubes Y to expel the candles therefrom. g is an endless band, receiving motion from the shaft I through the belt g^1 and pulleys g^2 g^3 , and made to circulate around the drums g^1 g^3 , which are journalled at the opposite sides of the machine, as represented in fig. 1. h h represent a pair of levers, which are supported upon transverse rod or shaft, h^1 , which is fitted to turn in lugs attached to the upper side pieces of the frame A . At their inner extremities these levers carry a pair of curved arms or rails, h^2 h^3 , which occupy positions at either side of the belt g . The upper ends of the levers h h are struck by the revolving arms or tappets on the shaft G , which has the effect to elevate the arms or rails h^2 h^3 to a position to receive the candles, after which h^2 h^3 fall by gravity and deposit the candles upon the belt g .

The operation will be readily understood from the above description of the functions and construction of the various parts of the apparatus, but I shall now give a brief description of the consecutive operations, and merely refer to the drawings by way of elucidation.

The material from which the candles are to be formed is first supplied to the mills or chambers B B , from which it is forced downward so as to fill the spaces in front of the pistons L L . The latter are then advanced toward the centre of the machine, carrying with them, and depositing beneath the plunger N , sufficient quantity of material for a single operation. The plunger N then descends and forces the material downward into the chamber Q , from which it is forced into the moulds by the forward movement of the plunger S , and pistons S^1 . As soon as the piston S reaches the receiving end of the mould R , its motion is reversed, but the forward motion of the cylindrical pistons S^1 is continued, so that they start out of their chambers in the plunger and enter the moulds, at which point in the operation the clamps d d open to permit the candles to be expelled by the advancing pistons; said clamps having, up to this time, maintained their closed position, so as to form a base or backing for each of the moulds. The candles having been expelled from the moulds R , the wicks, at the point of delivery, are seized by the closing clamps, and held while under the cutting action of the knife W , which detaches so much of the wick as belongs to that set of candles. The pistons, S^1 , having traversed the full length of the moulds R , and performed their special function, fly quickly back into their chambers within the plunger S , which had previously receded to allow another quantity of material to be forced into the chamber Q by the plunger N . The wick-tubes a are carried forward in the moulds R simultaneously with and to nearly the same extent as the pistons S^1 ; but while the pistons leave the moulds with a sudden impulsive movement, the wick tubes recede therefrom more slowly, and said wick-tubes, thus receding, thread the wicks, so to speak, in the centre of the candles as the material to form the latter is forced into the moulds by the readvancing plunger and pistons. During the backward or receding motion of the wick-tubes a , the wick, still held at the end by the clamps d d , is paid off from the reels T T in just sufficient quantity to supply one set of candles. When the candles start out of the moulds R , under the expelling action of the pistons S^1 , the tubes Y^1 , with their box Y , move toward the mould box R^1 , to receive and support the candles. After the wicks have been cut by the knife W , and released by the clamps d d , the box Y retreats from the moulds, and the stationary pistons Y^2 , entering the tubes Y^1 , expel the candles from the latter. Being thus delivered from the tubes Y^1 , the candles are received upon the arms or rails h^2 , which had risen to the height of the tubes to receive them. The arms, h^2 , descend and deposit the candles in a complete condition upon the band g , which carries them off as fast as they are made. The tubes, Y^1 , serve to give additional polish and solidity to the candles, and both they and the moulds R may be surrounded with ice, water, or a freezing mixture, if desired. The number of the moulds and tubes is unlimited, and the length of the candles can be regulated by the stroke of the pistons.

Having thus described my invention, the following is what I claim as new, and desire to secure by Letters Patent:

- I claim the receiving and reducing mills B C C^1 , supply chambers L^1 L^1 M Q , pistons L L^1 , plungers N S , and moulds R , all combined and arranged substantially as and for the purpose specified.
- I claim the pistons S^1 , operating in combination with the plunger S , and moulds R , substantially in the manner and for the purpose set forth.
- I claim the combination with the plunger S , and pistons S^1 , of the wick-tubes a , arranged and operating substantially as described.
- I claim the clamps d d , arranged and operating substantially as and for the purpose set forth.
- I claim the receiving and discharging tubes Y^1 , when arranged and employed in the manner and for the purpose set forth.
- I claim the combination with the tubes Y^1 , of the stationary pistons Y^2 , arranged and operating in the manner and for the purpose specified.
- I claim the box Y , affording a bearing and enclosing case for the tubes Y^1 , and reciprocated therewith by the means and for the purpose described.
- I claim the arms or rails h^2 h^3 , and levers h h , arranged and operating substantially as and for the purpose specified.
- I claim the endless band g , arranged and operating in the manner and for the purpose set forth.

10. I claim the combination with the reducing mills or chambers B B, of the steam chests or jackets B' B'
substantially as described.
11. I claim the knife W, when operated in the manner specified and employed in connection with the clamps
d d, for the purpose set forth.
12. I claim the combination of the dog U, with the reels T T, for limiting the let-off motion, as described.
13. I claim the within-described candle-making apparatus, consisting of the receiving mills or chambers
B B, supplying chambers L' M Q, plungers and pistons N S S' L L, wick-tubes a, reels T T, and clamps d d,
all arranged and operating substantially as set forth.
